TILE SURFACED STRUCTURAL ELEMENT

Filed July 28, 1931

UNITED STATES PATENT OFFICE

JOSEPH F. DOVEN, OF ZANESVILLE, OHIO, ASSIGNOR TO AMERICAN TILE FIXTURE COMPANY, INC., A CORPORATION OF OHIO

TITLE-SURFACED STRUCTURAL ELEMENT

Application filed July 28, 1931. Serial No. 553,678.

This invention relates to improvements in tile-surfaced structural elements of reinforced-cementitious material for soda fountain counters and the like.

One of the objects of this invention is to produce a tile-surfaced structural element of reinforced-cementitious material, for use in portable tile equipment such as soda fountain counters, which will have anti-warping properties, whereby tile units embedded in the surface of the cementitious material will be retained in proper position on the said surface and the tendency which accompanies warpage to break the bond between the tile units and the cementitious material is eliminated.

With these and other objects in view the invention comprises the combination of members and arrangement of parts so combined as to coact and cooperate with each other in the performance of the functions and the accomplishment of the results herein contemplated, and comprises in one of its adaptations the species or preferred form illustrated in the accompanying drawing, in which:—

Fig. 1 is a front elevation of a metallic angle-iron frame employed in making a tile-surfaced panel of cementitious material embodying my invention;

Fig. 2 is a cross-section on the line 2—2 of Fig. 1;

Fig. 3 is an enlarged fragmentary section showing tensioning elements applied to angle bar frame members;

Fig. 4 is a vertical section of a panel after the cementitious material has been pounded in a tensioned frame and tile units have been embedded in said cementitious material;

Fig. 5 is a fragmentary rear view showing two panels connected together.

Referring now to this drawing which illustrates a preferred embodiment of my invention, 1 indicates an angle-iron frame for a structural element or panel embodying a normally-warpable thin slab of cementitious material. The top and bottom members 3 and 3' and the side members 2 and 2' of the frame have reinforcing wires 4 and 5 attached thereto and stretched across the frame opening and each of said frame members 2, 2' and 3 and 3'

are provided with a tensioning member 6 comprising a metallic strip or steel latch which is fastened preferably by electric arc welding at its opposite ends 6' to the inner surface of the bottom or base flanges of the angle-iron bars, comprising the frame 1. Said strip 6 is free and unconnected at its central portion and at said central unconnected portion provided with a tapped hole 6^a through which an adjustable tensioning screw 7 is threaded so that its point engages or impinges against the inner surface of said bottom flange to which the strip is attached. Obviously upon being screwed or rotated in the tapped hole 6^a the said screw will cause the central portion of the strip 6 to be gradually raised and tension to be applied in accordance with the depth of the screw which is screwed through the tapped hole 6^a. By this operation, a bowing tension will be applied on the bars of the frame and this bowing tension may be employed to offset and counteract the tendency to warp that normally occurs when a relatively thin slab 8 of cementitious material, mounted in a frame of this type contracts. I am thus enabled to provide a flat embedding surface to be produced on such slab for tile units 9, permitting the tile units to be retained in properly embedded relationship with the cementitious slab and avoiding or eliminating the tendency of the tile units to separate and peel off, which happens in elements of this character when the backing slab becomes warped. It will be seen, therefore, that by my invention I counteract such tendency to warpage as would normally occur and at all times present a flat unbowed and unwarped surface for the embedding and secure attachment of the tile units.

In the preferred form of my invention, I proceed as follows:—

The steel angle-iron frame 1, which is usually rectangular in conformation is fabricated in any suitable manner and has fastened to the inner surface of each of the base or bottom flanges at the sides 2 and 2' and top and bottom 3 and 3' of the frame the tension members hereinabove referred to. This is preferably accomplished by a superimposing on each of such flanges of a metallic ten-

sion strip or steel lath and fastening this tension strip or steel lath at its opposite ends, preferably by electric arc welding, to the said flanges. The ends only of such strips are fastened so that the central portion of each of the strips will remain free and unattached to the flange. This central portion of the strip is, as aforesaid, provided with a tapped hole into which is threaded a screw. The frame 10 so provided with a tension strip in complete abutment with its flange is laid on a smooth surfaced pouring table and securely fastened thereto in any suitable manner, such as by the use of clamps. When the frame has thus been 15 securely fastened to the pouring table, tension is then applied between the metallic tension member and the flange of the angle-iron members of the frame by screwing of the screw through said tapped hole, as much tension 20 preferably being applied as is possible. During this tension-applying operation the frame is held securely in abutment with the pouring table; and while the frame is thus tensioned and held in flat condition, the cementitious 25 composition, preferably comprising haydite and cement is poured into the frame to a suitable depth. Thereafter the tile units are set or embedded into the top surface of the cementitious material in accordance with the 30 design which it is desired to utilize in any particular construction element or in any particular structure of which such element is to form a part. The structural element, which now comprises the tensioned metallic frame, 35 the poured slab of cementitious material with tile units embedded in its upper surface is maintained in flat position for a period of approximately forty-eight hours by which time the slab and the units and other parts of the 40 said structural element will have acquired sufficient bond to permit the structural element to be released from the pouring table and to be moved into perpendicular position.

Under normal circumstances, the process 45 of warpage would now start, but by the use of my tensioning members, I have been enabled to offset or counteract the warpage which would otherwise take place and thus to eliminate such warpage in the structural 50 element.

It is thought that when the cementitious slab of a structural element of this nature starts warping or bowing and the tile bond is broken, it is caused by the tile surface formed 55 of tile units remaining constant while the portion formed of hardened cementitious material contracts, and by the use of my invention, the tension created through the tensioning of the tension strips or steel lath will cause 60 a pull in the direction opposite to that in which the contraction of the cementitious material would cause the panel to warp.

As many changes could be made in the above construction and many apparently 65 widely different embodiments of this inven-

tion could be made without departing from the scope thereof; it is intended that all matter contained in the above description or shown in the accompanying drawing shall be interpreted as illustrative and not in a limiting sense. 70

Having described my invention, I claim:—

1. A constructional element embodying, in combination a flat relatively thin and normally-warpable slab of cementitious material, a reinforcing member embedded in said slab, and means for applying a bowing tension to said reinforcing member to counteract the normal warpage of said slab. 75

2. A constructional element embodying, in combination a flat, relatively thin and normally-warpable slab of cementitious material, a metallic reinforcing member embedded in said slab, and means for applying a bowing tension to said metallic reinforcing member to counteract the normal warpage of said slab. 80

3. A constructional element embodying, in combination a warpable body composed of a flat, relatively thin and normally-warpable slab of cementitious material, a reinforcing member embedded in said slab comprising a metallic frame, and means for applying a bowing tension to said frame to counteract the normal warpage of said slab. 90

4. A tile-surfaced constructional element embodying, in combination a flat, relatively thin and normally-warpable slab of cementitious material, a metallic reinforcing member embedded in said slab, tile units embedded in one surface of said slab and means for applying a bowing tension to said metallic member to counteract the normal warpage of said slab. 100

5. A tile-surfaced constructional element embodying, in combination a flat, relatively thin and normally-warpable slab of cementitious material, tile units embedded in one surface of said slab, metallic reinforcing member embedded in said slab comprising a metallic frame and means for applying a bowing tension to said frame to counteract the normal warpage of said slab. 110

6. A tile-surfaced constructional element embodying, in combination a relatively thin and normally-warpable slab of cementitious material, tile units embedded in one surface of said slab, metallic reinforcing member for said slab comprising a metallic frame composed of angle-bars, metallic laths fastened at opposite ends to one of the flanges of said angle-bar frame and having its middle portion free and means abutting between said flanges and the free middle portion of the lath to apply tension on the said frame. 115

7. A tile-surfaced constructional element embodying, in combination a relatively thin and normally-warpable slab of cementitious material, the units embedded in one surface of said slab, metallic reinforcing member for 120

- said slab comprising a metallic frame composed of angle-bars, metallic laths fastened at opposite ends to one of the flanges of said angle-bar frame and having its middle portion free and screws threaded in said middle portion of the laths and impinging against said flanges of the frame for applying tension in said frame to counteract the normal warpage of said cementitious slab.
- 5 8. A method of producing construction elements of cementitious material comprising the fabricating of a metallic frame, applying thereto a tensioning member adapted to bow said frame, fastening of said frame to a flat surface, applying a bowing tension by said tensioning member to said frame while so fastened and restrained from bowing and held in flat position, pouring a cementitious material into said tensioned and restrained frame to provide a slab of cementitious material, embedding tile units into the upper surface of said slab of cementitious material, retaining said frame and cementitious slab with the tile units embedded therein for a 10 predetermined period of time to permit bonding between said parts, and subsequently releasing said construction element from said flat surface.
- 15 In witness whereof, I have signed my name
20 to the foregoing specification.
